PLASTIC FABRIC OR THE LIKE

Robert Charles Lewis, Westbury, N. Y., assignor
to United Merchants and Manufacturers, Inc.,
New York, N. Y., a corporation of Delaware

Application November 20, 1952, Serial No. 22,388

Term of patent 14 years

(Cl. D87—3)

To all whom it may concern:

Be it known that I, Robert Charles Lewis, a citizen of the United States, residing in the village of Westbury, in the county of Nassau and State of New York, have invented a new, original, and ornamental Design for a Plastic Fabric or the like, of which the following is a specification, reference being had to the accompanying drawing, forming a part hereof.

The figure is a plan view of a plastic fabric or the like showing my new design. The broken lines on the drawing outline a design unit, which unit is repeated in regular succession as indicated by the extensions beyond the unit boundary.

I claim:

The ornamental design for a plastic fabric or the like, as shown and described.

ROBERT CHARLES LEWIS.
